Primary Examiner — Caron D Veynar*Assistant Examiner* — Katrina N Gonzalez(57) **CLAIM**

The ornamental design for a cosmetic container, as shown and described.

DESCRIPTION

FIG. 1 is a front top right perspective view of a cosmetic container showing my new design;

FIG. 2 is a rear bottom left perspective view thereof;

FIG. 3 is a front elevational view thereof;

FIG. 4 is a rear elevational view thereof;

FIG. 5 is a left side elevational view thereof, the right side elevational view being a mirror image;

FIG. 6 is a top plan view thereof;

FIG. 7 is a bottom plan view thereof;

FIG. 8 is another perspective view of FIG. 1 shown with unclaimed surface indicia applied; and,

FIG. 9 is an enlarged detail view of area 9 of FIG. 8, showing unclaimed surface indicia.

The broken lines shown in FIGS. 8 and 9 depict environmental subject matter that forms no part of the claimed design.

The usage of the cosmetic container is to store materials in cream or emulsion form.

1 Claim, 8 Drawing Sheets(56)
